EXTENSION TABLE

Manuel Langius, Sparta, Mich., assignor to Michigan Artercraft Company, Sparta, Mich., a corporation of Michigan

Application March 27, 1939, Serial No. 264,348

2 Claims. (Cl. 311—59)

This invention is directed to a novel construction of extension table. With the present invention the table when not in use may be retracted to occupy relatively small space, no more than that generally occupied by an ordinary desk, but may be extended and enlarged to substantially any desired degree within the limits of the slide extensions used, so as to produce a table having a horizontal top of desired size, which after it has been used may again be retracted to its initial small size.

The invention may be fully understood from the following description, taken in connection with the accompanying drawings, in which:

Fig. 1 is a plan view of the table as it is undergoing the first steps of extension.

Fig. 2 is a transverse section through the extended table substantially on the plane of line 2—2 of Fig. 1.

Fig. 3 is a view similar to Fig. 2, showing the foldable top member unfolded and lying in the same plane with the fixed top section of the table.

Fig. 4 is a vertical section through the upper part of the table in its retracted condition.

Fig. 5 is a similar section with the table in extended position without extension leaves or fillers therein.

Fig. 6 is a view similar to Fig. 5 but with the table further extended and using filler leaves, and

Fig. 7 is a fragmentary vertical section similar to Fig. 4, illustrating the releasable lock which holds the parts in its retracted position.

Like reference characters refer to like parts throughout the different figures of the drawings.

In the construction shown, a horizontal top member 1 has vertical supporting posts 2 underneath the two outer corners thereof, between which is a depending apron 3, while from each post an end member 4 extends underneath and adjacent the ends of the top member or section 1, as shown in dotted outline in Fig. 1. Two extension slides are used and one of the end members 5 of each of the slides is permanently secured to and underneath the top member 1. Between the other end members 6 of the two series of slides are a plurality of intermediate slides 7, as shown, such extension slides being of a conventional and well-known character.

Associated with the outer slide members 6 and connected thereto are two additional posts 8 spaced apart from each other like the posts 2, and having between them an apron 9 similar to the apron 3, while extending therefrom in planes at right angles to the apron 9 are end members 10, lying along the outer sides of the end slides

6 and secured thereto. A board 11 extends between and underneath the end slides 6 and is secured at its ends thereto, having its outer edge connected to the inner side of the apron 9 and at its inner edge being recessed to provide an elongated recess as shown at 12. It is evident that the posts 8 and connected parts may be moved inwardly so that the upper ends of the posts will come underneath the other corners of the fixed top member 1, and with the end members 10 coming inside the end members 4, in which position the table will have a top area consisting only of the member 1.

On the upper side of the board 11 and one side of the middle thereof a block 13 is permanently secured, which, adjacent its inner end, carries a supporting bracket 14 through which a rod 15 passes. The rod at its outer end is flattened and bent down and permanently secured to the block 13, the rod in the retracted position of the table 20 extending underneath the top member 1, as shown in Fig. 4. One section 16 of a foldable top member is mounted on the rod 15 by means of spaced brackets 17 connected to the section 16 and through which rod 15 freely passes. The outer end of the rod 15 is up-set to make stops 18 whereby the brackets 17 may not disengage from the rod. However, it is evident that the brackets 17 may be moved along the length of the rod within the limits prescribed by the two stops 14 30 and 18 against which the opposite brackets 17 will come when moved in opposite directions. A second member 19 of the same size as the part 16 is hinged at 20 to one edge thereof and in the folded position lies underneath the upper part 35 16 and at one corner bears upon the upper side of the board 11 beyond one end of the recess 12 therein.

By turning the folded top section consisting of the two parts 16 and 19 in a clockwise direction (Fig. 2) about the axis of the rod 15, the upper section 16 will be extended outwardly, as shown in Fig. 3 and pass over the members 6 and 7 of one of the slides and the adjacent end member 10, and the then uppermost section 19 may 45 be swung counterclockwise about the hinges 20 to lie in the same plane with the section 16. When thus unfolded an addition to the top is provided, the two sections 16 and 19 being in the same plane with the fixed top section. Each 50 of the sections 16 and 19 has a metal bracket 21 secured thereto, which in the unfolded position as in Fig. 3 of the foldable top member, extend downwardly from the under sides of the parts 16 and 19. After the foldable top section 55

has been unfolded and brought to the position shown in Fig. 3, it is moved on the rod 15 toward and over the upper edge of the apron 9 until the stops 21 come against the inner side of said 5 apron, whereupon the foldable top section is properly located with respect to the posts 8. Thereafter, if the table is to be no further enlarged, the slides are retracted until the adjacent edges of the parts 16 and 19 and of the top 10 member 1 are brought together as in Fig. 5. In the movement of the foldable top member outward to bring the stops 21 against the apron 9, the section 19 is carried upwardly and over the inclined leg of an angle bracket 22 (Fig. 7) 15 secured at the inner side and near the upper edge of the apron 9, thus insuring that the outer edges of the parts 16 and 19 will not abut against the inner upper edge portions of the apron 9.

When the table is retracted as in Fig. 4, it is 20 held in such position by a releasable locking means best shown in Fig. 7. A block 23 is secured to the upper side of the board 11 substantially on the median line of the table, through which and the board 11 a locking pin 24 passes, its lower end being connected with a manual release member 25 of spring material which is fully 25 shown and described in application Serial No. 259,941 filed March 6, 1939. A keeper block 26 has a recess in its under side and has a cam edge 30 underneath which the upper end of the pin 25 rides until the recess is reached; the spring member 25 yielding and when the recess is reached moving the upper end of the pin 25 into said recess. The pin may be released by manual operation 35 of the member 25 when an extension of the table is contemplated. There is also associated with the table a foldable center supporting leg of the same construction shown in my pending application, Serial No. 206,775, filed May 9, 1938. 40 The horizontal board 27 extends between and is secured to the under side of slides 7 of the two series of slides and said board is slotted from one end for a greater portion of its length, with a slide block 28 mounted in the slot through which 45 the foldable leg 29 is connected at its upper end. When the table is retracted the leg is folded upwardly as in Fig. 4, but when it is extended it is turned downwardly as in Figs. 5 and 6 and is automatically positioned substantially at the center 50 of the table.

As shown in Fig. 6, the table may be further extended beyond the size shown in Fig. 5, and between the permanent top section 1 and the foldable top section consisting of the parts 16 and 55 19, filler leaves 30 may be located which rest upon the upper edges of the slides 7.

The construction of table described is of a very practical and serviceable character. The extension of the table to either the position shown in 60 Fig. 5 or that in Fig. 6 is quickly and easily accomplished. The return of the table to the retracted position in which it occupies much less space is easily and readily done. The invention is one of great practical utility.

65 The claims appended hereto define the invention, which is to be considered comprehensive of all forms of structure coming within their scope.

I claim:

1. In a table, a horizontal top section, supporting legs connected therewith and extending downwardly substantially at its outer corners, extensible slides comprising end slide members and intermediate slide members, one of the end slide members of each of said extensible slides being connected to the under side of said top section, additional legs connected to the outer ends of the other end slide members and movable therewith, an apron located in a vertical plane between and connected at its ends to the upper portions of the legs, a horizontal board connected at one edge to said apron and extending inwardly therefrom, having its ends secured to 10 and at the lower sides of said other end slide members, said board adjacent its inner edge having a relatively long recess therein, a horizontal rod connected and supported at one end on said board and extending inwardly away from the 20 apron, a foldable top section comprising two substantially equal parts hingedly connected end to end, and spaced brackets secured at one side of one of said parts of the foldable top section through which the rod loosely passes, said foldable top section in folded condition being adapted to be turned about the axis of said rod through the recessed portion of said board through substantially 180° and thereafter unfolded to bring the two parts into alinement and into the same 25 horizontal plane with the first top section.

2. In a table, a horizontal top section, supporting legs connected therewith and extending downwardly substantially at its outer corners, 30 extensible slides comprising end slide members and intermediate slide members, one of the end slide members of each of said extensible slides being connected to the under side of said top section, additional legs connected to the outer ends of the other end slide members and movable therewith, an apron located in a vertical plane between and connected at its ends to the upper portions of the legs, a horizontal board connected at one edge to said apron and extending inwardly therefrom, having its ends secured to 40 and at the lower sides of said other end slide members, said board adjacent its inner edge having a relatively long recess therein, a horizontal rod connected and supported at one end on said board and extending inwardly away from the 50 apron, a foldable top section comprising two substantially equal parts hingedly connected end to end, spaced brackets secured at one side of one of said parts of the foldable top section through which the rod loosely passes, and stop means 55 at the free end of the rod for preventing disconnection of said brackets with said rod, said foldable top section in folded condition being adapted to be turned about the axis of said rod through the recessed portion of said board 60 through substantially 180° and thereafter unfolded to bring the two parts into alinement and into the same horizontal plane with the first top section.

MANUEL LANGIUS. 65
